DEFECATOR WITH UNIVERSAL WALL OR
FLOOR OUTLET CONNECTIONWilliam C. Groeniger, Columbus, Ohio, assignor
to John B. Pierce Foundation, New York, N. Y.,
a corporation of New York

Application November 17, 1937, Serial No. 174,919

3 Claims. (Cl. 4—252)

This invention relates to defecators.

The invention is applicable to defecators inclusive of water closet bowls, urinals, and hospital and other sinks, dental, medical and other sanitary bowls or receptacles, provided with suitable means for the supply of water or equivalent effluent, such effluent affording under sanitary conditions a mass of fluid for a well portion of the defecator, serving to receive solid and/or semi-solid and/or fluid matter to be evacuated, and further providing for flushing the defecator to discharge such flowable mass into a soil pipe or equivalent waste disposal system.

Defecators embodying the present invention are preferably, but not restrictively, of the floor-supported type, i. e., having such configuration of side-walls and/or leg supporting members as to make the defecator, as a unit, self-supporting in character.

It is a feature of the invention that the connection of the discharge port of the defecator to the customary soil pipe or waste pipe is above the floor level, and preferably is disposed below the defecator bowl and substantially centrally located within the compass of the complete defecator structure, full access being afforded to the point of such discharge port connection.

Thus, the defecator may be positioned at its ultimate location prior to its connection to the soil pipe, such connection thereby being made under most advantageous conditions. The facility with which a soil-pipe connection may be made in a defecator embodying the present invention minimizes the possibility of leaky or otherwise defective connections.

Additionally, this invention renders the connection of the defecator with the soil pipe at all times accessible for inspection or repair, such inspection necessitating merely the removal or opening of suitable closure means disposed adjacent the stated point of connection.

Further, this invention provides a defecator which is universally applicable for connection to floor outlet or wall outlet soil pipes, the organization of such defecator discharge port connection means affording an especially wide latitude of connection with the soil pipe or equivalent, and obviating the customarily required meticulous accuracy of installation of the soil pipe.

In this invention, the bowl structure of the defecator is supported clearly above the floor, as by suitably arranged and configurated side walls which are arranged to rest upon the floor and support the entire structure. By suitable

means, the terminal end of the discharge passage of the defecator is horizontally and rearwardly directed, such passage lying at the floor level, and having the plane of its discharge port in vertical relationship to the plane of the floor. Advantageously, the discharge port lies adjacent a low point of the bowl, substantially centrally within the compass of the structure and intermediate suitable offset wall-portions of the defecator structure; such wall portions advantageously serve as members to which suitable soil-pipe connection devices may be secured.

To afford ready access to such point of connection, thus facilitating the original installation or subsequent inspection thereof, the side walls of the bowl structure adjacent the point of connection may be provided with openings of suitable size and configuration. Preferably, closure means for such wall openings, such as suitable removable doors or cover plates are provided.

Advantageously, at least one such opening is provided in each side wall of the defecator structure, the stated openings thus providing for a sidewise, above-the-floor entry of a soil pipe through the stated wall and into position for connection to the waste-outlet of the defecator.

Other features and advantages hereinafter appear.

In the accompanying drawings:

Fig. 1 is a vertical section of a defecator embodying the present invention, the soil pipe connection therewith being of the wall-outlet type;

Fig. 2 is a plan view of the defecator of Fig. 1;

Fig. 3 is a section taken on the lines 3—3 of Fig. 1, Fig. 3 showing a sidewardly directed defecator discharge pipe connecting into a wall-outlet soil pipe;

Fig. 4 is a front elevation of the defecator of Fig. 1;

Fig. 5 is a vertical section taken through the lower portion of a defecator at the point of defecator waste-outlet connection, further illustrating a connection with a floor-outlet soil pipe; and

Fig. 6 is a view similar to that of Fig. 5, illustrating the connection to a conventional vertical soil pipe run.

Referring to Figs. 1 and 4, a floor-supported defecator 10 includes a base 11 arranged to rest upon a finished floor 12 of a room or other enclosure housing the defecator, and further includes preferably vertical side-walls, the rear portions 13, 13 thereof, as shown in Fig. 3, sub-

stantially defining the maximum width of the structure, and the front portions 14, 14 thereof serving to establish side walls of an evacuator leg, as later described. Each pair of walls 13, 14 5 is preferably joined by an integral offset wall 15. The defecator may further include a back plate 16, arranged to effect a snug connection with a wall 17 of the room or enclosure, the wall structures of the defecator combining with the floor 10 12 and wall 17 to define a closed chamber 18.

Desirably, the defecator is of a conventional 15 ceramic material, the component parts of the defecator being so united during the manufacture thereof as to present a substantially integral finished structure.

The defecator may have a bowl, comprising an upper portion 19 and a lower or well portion 20; a rear wall 21 of the bowl cooperates with a suitable wall structure 22 to form a water flow 20 passage 23 having a jet opening 24 at the well portion 20 of the bowl. Water or equivalent liquid for flushing the defecator may be admitted through a port 35 served by a flushometer valve, supply tank or other conventional means. The 25 normal level of the mass of water or other matter-receiving and effluent fluid is indicated at 25. Such mass of fluid serves as the trap sealing fluid. The normal level 25 of the fluid may be established by a dam 26 formed by the upper limit of 30 a forwardly and upwardly extending wall 27, such wall being in effect a continuation of wall 22. A ledge 28 cooperates with wall 27 in defining a forwardly and upwardly extending passage 29, leading from well portion 20 and serving as the 35 anterior leg of a waste-discharge or evacuator system. A downflow passage 30 of the evacuator system is defined by the side walls 14, a front wall 31 and a rear wall 32, the latter preferably being integral with the wall 21. Thus, the downflow 40 leg 30 may be in the most forward location of the defecator structure and constitute one of the supporting elements thereof.

The downflow leg 30 communicates with or is 45 integral with a preferably substantially horizontal outflow leg or discharge passage 33, the stated outflow leg having a preferably belled discharge port 34 adaptable for connection with a waste-disposal means, such means being typified by a conventional soil pipe and/or an intermediate conduit for effecting such connection between the defecator and a soil pipe. The discharge port 50 34 of outflow leg 33 is preferably contiguous with the offset wall-portions 15; such construction appreciably strengthens the structure of the port 34, and advantageously provides a trans- 55 verse bracing rib 36, see Fig. 1.

An inflow of flushing liquid serves to initiate flow of the contents of the bowl upwardly through 60 passage 29, downwardly through passage 30 and rearwardly through the discharge passage 33, a 65 preferably 180 angular degree change in direction of flow thus being afforded by the organization of the stated passages.

As clearly indicated in Figs. 1, 5 and 6, the 70 discharge port 34 preferably lies above the floor line and at a point adjacent the front central portion of the bowl, the lowest point of the latter, as shown, lying above and to the rear of the port 34. Most preferably, the plane of the discharge 75 port is perpendicular to the stated floor line. Such disposition of discharge port 34 provides for full accessibility of the point of soil pipe connection, wide latitude in the characteristics of such connection, and appreciably strengthens

the bowl structure, a preferably integral web 27a supporting wall 27 on the rim of port 34.

To facilitate the connection of the soil pipe to discharge port 34, and to make the completed installation thereof at all times accessible for inspection or repair, there is preferably provided in each of the side walls 13, an opening 37 of suitable area and configuration. Such openings afford adequate access to the lower interior of the chambered portion 18 of the defecator structure, and thereby make it possible for the workman to place the defecator in its ultimate location and to pass the fittings necessary for the connection through the stated openings, the soil pipe connection thus being made with a facility hitherto unattainable in a floor-supported defecator. Preferably, suitable closure plates 38 may be employed to conceal the soil pipe connection from view. Such closure plates may be removably secured to the wall structure as by the 20 spring clips 39 or equivalent.

Connection of the defecator with the soil pipe, the latter being shown in the drawings as being of the nature of a stack or riser 40 may be effected by a suitable intermediate conduit 41, the connection thereof with the soil pipe advantageously being screw-threaded or equivalent, as shown in Fig. 6. Connection with the discharge port 34 may be of a slip-fit type, such connection being made gas and fluid tight by suitable organization of packing means and associated structure. A ring of suitable packing, as 42, Fig. 3, is arranged to be compressed about the conduit 41 and into the belled mouth 34 by a suitable yoke 43, bolts 44 and nuts 45 serving to draw the yoke forwardly to exert a compressive force on such packing. The bolts 44, as clearly indicated in Figs. 3 and 4, pass through the offset wall-portions 15 of the side walls of the defecator structure, and the nuts 45 thereby bear against the external surface of such wall portions, which thereby serve as anchoring members. The nuts 45 are thus rendered fully accessible from outside the defecator, facilitating the operation of making the connection, and reducing the work performed within the chamber 18 to a mere insertion and positioning of the requisite parts.

The stated location of the discharge port 34 above the finished floor line and at a point near the front central portion of the bowl, permits the 50 soil pipe conduit 41 to be carried above the floor to meet a wall outlet soil pipe, see Figs. 1 and 3, or to connect to a floor outlet soil pipe at any one of a variety of locations, as typified by Figs. 5 and 6.

As particularized in Fig. 3, the soil pipe 40 may 60 of necessity be run behind a wall at one side or another of the defecator, a conventional elbow being provided for purposes of connection. Such soil pipe organization is readily connectible to the discharge port 34, it being necessary merely to bring the connection 41 through the appropriate opening 37 of a wall 13 and into the lateral of the elbow.

As indicated in Fig. 5, a vertical soil pipe riser 65 may terminate within the confines of the side walls of the defecator, whereupon connection 41 may comprise a short elbow connection. In yet another circumstance of soil pipe organization, as shown in Fig. 6, the connection to the soil pipe may be had by a suitable S-shaped connection, carrying below the finished floor line and into the lateral of the soil pipe elbow connection.

As is shown in Figs. 1 and 2, the connection

with the soil pipe may be made directly rearwardly. Fig. 1 emphasizes that the projecting collar 42 of the soil pipe lateral may project into the space 18 formed beneath the defecator structure; thus the depth of partition or wall housing the soil pipe may be of minimum dimension.

From the aforesaid, it appears that the invention provides for connection of the discharge of the defecator in any direction as desired to a soil line or intermediate conducting passage, above the floor line, and when required or desired to a soil line through the conventional opening through the floor.

Whereas I have described my invention by reference to specific forms thereof, it will be understood that many changes and modifications may be made without departing from the spirit of the invention.

I claim:

1. A floor-supported defecator constructed for connection concealed within the defecator structure with a soil pipe located optionally within a building wall relative to which the defecator is set in predetermined position, or accessible through the floor, said defecator comprising, in combination, a bowl, a defecator wall structure supporting the bowl, means for discharging the contents of the bowl into such soil pipe, said means including an anterior syphon leg, a posterior syphon leg, and a horizontally directed out-flow passage having its terminus disposed substantially centrally of the vertical boundaries of said bowl supporting wall structure and intermediate a low point of the bowl and the plane of the base of the defecator wall structure, one of said bowl supporting wall structures being disposed transversely of the bowl adjacent said out-flow passage terminus, and means cooperating with said transversely arranged bowl supporting wall for the securement of suitable piping leading to such soil pipe.

2. A floor-supported defecator constructed for connection concealed within the defecator structure with a soil pipe located optionally within a building wall relative to which the defecator is set in predetermined position, or accessible through the floor, said defecator comprising, in combination, a bowl, a bowl supporting defecator

wall structure including a wall extending transversely of said bowl and mutually spaced side walls cooperating with said transverse wall to form an open-bottom and open-ended chamber, means integral with said bowl for discharging the contents of the bowl into piping leading to such soil pipe, said means including an anterior syphon leg, a posterior syphon leg, and a horizontally directed out-flow passage having its terminus disposed within said chamber adjacent 10 said transverse wall and substantially centrally of the vertical boundaries of said bowl supporting wall structure and intermediate a low point of the bowl and the plane of the base of said wall structure, said side walls having openings arranged in operative association with said out-flow passage terminus, and means cooperating with said transversely arranged bowl supporting wall for the securement of said piping leading to such soil pipe.

3. A floor-supported defecator constructed for connection concealed within the defecator structure with a soil pipe located optionally within a building wall relative to which the defecator is set in predetermined position, or accessible through the floor, said defecator comprising, in combination, a bowl, wall means masking said bowl and arranged to support said defecator upon a floor slab, said wall means including a wall arranged transversely of said bowl and spaced side wall means cooperating with said transverse wall to form a chamber of substantial volume, said chamber having an open bottom and an open end, and evacuator means for said bowl, including a forwardly directed anterior syphon leg, a posterior syphon leg, and a rearwardly directed out-flow passage disposed beneath said bowl, the terminus of said out-flow passage being within said chamber adjacent said transverse wall means, said side wall means having mutually aligned closable openings arranged in operative association with said out-flow passage terminus to accommodate the passage of sidewardly directed soil pipe connection means and said transverse wall having means whereby said soil pipe connection means may be secured in operative association with the terminus of said rearwardly directed out-flow passage.

WILLIAM C. GROENIGER.
